PASQUALE GALASSI, OF NEW YORK, N. Y.

INTERLOCKING FLOOR STRIP.

Application filed May 16, 1928. Serial No. 278,172.

This invention relates to improvements in means for laying and constructing terrazzo and similar floors, and more particularly refers to dividing strips such as are used for defining and separating the various panelled sections of which a terrazzo floor is composed.

Strips of this character have heretofore been made in one piece of the proper width and thickness according to requirements, said strips being generally provided with anchoring and positioning means formed by isolating portions of the material and by bending said isolated portions laterally of the strip.

These strips are generally made of brass or other suitable metal and are used in various thicknesses for ornamental or structural reasons or both. However a heavy gauge metal is in most cases only used for ornamental reasons, and therefore a thick section of metal is actually only needed at the top where it shows through the floor. It is common practice, on the other hand, to use metal of uniform gauge all through, and this is likely to considerably increase the cost of the floor, especially when brass is used.

At times strips have been rolled in special shapes comprising a relatively wide head portion and a relatively thin body portion, but these special shapes are bound to be more expensive than standard materials of the same weight.

Furthermore as a general rule it is desirable to use brass only at the top of the strip and to use a less expensive material for the body thereof even when light gauge strips are concerned, for the resulting saving in the cost of material is sufficient to profitably compensate the increased labor costs entailed by the joining of the two portions into a single structure. The advantage thus resulting is of course greater in the case of strips having a relatively wide section at the top, as will be understood.

In another application entitled "Composite flooring strips", Ser. No. 252,323, I have described and claimed a bimetallic strip of special construction in which the upper and lower sections of the strip are joined together by means of transversely and longitudinally interlocking male and female joints. In the said application I also have described constructions whereby the anchoring and positioning means may be produced directly by bending laterally of the strip the

body portions isolated in order to produce part or all of the notches forming part of the interlocking joints, furthermore I have mentioned among others the possibility of securely joining the two strips by, either by making the tenons of one portion of the strip fit very tightly within the notches of the other section, or by welding or riveting operations or both.

The present invention is intended as an improvement over the constructions described and claimed in the said application, and its primary object is to provide a bimetallic strip composed of two sections interlocking with each other by means of male and female joints, in which some or all of the portions of metal isolated from one or the other section or both in order to produce notches therethrough are bent alongside the surface of the section connected thereto, securely locking the two sections together against relative lateral movement.

Another object of the invention is to provide a floor strip of the character specified in which some of the portions isolated to produce notches in one or the other of the sections composing the strip, or both, are bent alongside of the section connected thereto in order to securely lock the two sections against relative lateral movement, and some of said isolated portions are bent laterally of the strip to provide anchoring and positioning means for said strip.

Other objects and advantages of the present invention will more fully appear as the description proceeds and will be set forth and claimed in the appended claims.

Various embodiments of my invention are illustrated in the accompanying drawings, in which:

Fig. 1 is a fragmentary side view in elevation of an assembled strip embodying my invention in one of its forms;

Fig. 2 is a cross sectional elevation through lines 2-2 of Fig. 1;

Fig. 3 is a cross sectional elevation through line 3-3 of Fig. 1;

Fig. 4 is a fragmentary side view in elevation of a similar strip of a slightly different construction;

Fig. 5 is a cross sectional elevation through line 5-5 of Fig. 4;

Fig. 6 is a cross sectional elevation through line 6-6 of Fig. 4;

Fig. 7 is a fragmentary side view in elevation of a similar strip illustrating the pre-

ferred way of carrying my invention into practice;

Fig. 8 is a cross sectional elevation through line 8—8 of Fig. 7;

Fig. 9 is a cross section elevation through line 9—9 of Fig. 7;

Fig. 10 is a fragmentary side view in elevation of a similar strip of a somewhat different construction;

10 Fig. 11 is a cross sectional elevation through line 11—11 of Fig. 10;

Fig. 12 is a cross sectional elevation through line 12—12 of Fig. 10;

15 Fig. 13 is a cross sectional elevation through line 13—13 of Fig. 10;

Fig. 14 is a fragmentary vertical cross section of a floor showing the strip illustrated in Figs. 10 to 13 in position, at the same time illustrating the function of positioning and anchoring means offset therefrom;

20 Fig. 15 is a fragmentary side view in elevation of a strip of a different type also embodying my invention;

25 Fig. 16 is a cross sectional elevation through lines 16—16 of Fig. 15;

Fig. 17 is a cross sectional elevation through lines 17—17 of Fig. 15;

30 Fig. 18 is a fragmentary side view in elevation of a similar strip of a somewhat different construction;

Fig. 19 is a cross sectional elevation through lines 19—19 of Fig. 18;

35 Fig. 20 is a cross sectional elevation through lines 20—20 of Fig. 18;

Fig. 21 is a view in perspective of the head section of the strip shown in Figs. 18 to 20;

40 Fig. 22 is a view in perspective of the rib or body section thereof before assembling; and

Fig. 23 is a view in perspective of the completed strip showing the manner of assembling the two sections together.

45 The strip illustrated in Figs. 1 to 3, is composed of an upper or head section 30 provided with notches 31 and a lower or rib body section 32 provided with tenons or male members 33 adapted to be laterally inserted

50 through said notches and to interlock therewith. Said tenons are formed by slitting the metal about their sides and bending outwardly the metal portions thus isolated to form extended ears or lugs 34.

55 In the construction shown, said ears or lugs are all bent at the same side of the strip and form a fractionated horizontal flange which may be used as a positioning means determining the depth at which the strip

60 may be inserted through the bed of the floor, the distance between the upper edge 35 of the strip and the lower surface 36 of the ears or lugs composing the flange being about equivalent to the thickness of the finishing

65 layer of the floor.

In so far as described, the strip corresponds to the type of structures described and claimed in my other patent above referred to. The new feature to which the present invention is more particularly directed is the provision of means for restraining the two sections of which the strip is composed against relative lateral movement, once the strip is assembled.

70 In the present case, this end is attained by forcing or riveting the edges of notches 31 about the edges of tenons 33, causing the material about the edges of the notches to extend inwardly and to overlap the side surfaces of the tenons near the edges thereof, as shown at 37. The resulting strip becomes thus composed of two sections which are securely locked to each other in all directions, and which to all intents and purposes will act as a single body of material.

75 The strip illustrated in Figs. 4, 5, 6, is similar in all respects to the one just described, except that its lugs or ears 38, 39, extend laterally of the strip part at one side and part at the other, being preferably arranged in alternate sequence as shown.

80 By virtue of this construction, the supporting and positioning action of said lugs or ears is made more effective, assuming correct vertical alignment of the strip when it is laid in position. It will be observed that both of the strips so far described, comprise a head portion 30, 40, the section of which is wider than the section of the rib or body portion 42, 41; and in fact this is the condition that makes it possible to extend the edges of the notches of the wider portion over the edges of the tenons of the narrower portion.

85 The relative lateral displacement of the sections of which the strip is composed can also be prevented by bending part or all of the lugs or ears laterally extending from one of the members towards and to overlap the surface of the other member. This manner of locking the two sections of the strip together represents the preferred embodiment of my invention and is illustrated in Figs. 7 to 9, in which the strip is shown composed as in the previous cases of upper 90 or head section 42, provided with evenly spaced notches 43 along its inner edge, and a lower or body section 44 provided with tenons 45 adapted to be laterally inserted through and to interlock with said notches.

100 Like in the previous case the tenons are formed by slitting the metal about their sides and bending outwardly the metal portion thus isolated; with the difference that when the two sections of the strip are assembled, the laterally extending ears or lugs thus formed, are bent upwardly about the lower edges of the upper section to overlap the sides thereof, as shown at 46, 47. In this manner, after the strip is assembled,

its two sections cannot be taken apart, being securely locked, not only against longitudinal and vertical relative displacement but also against lateral displacement.

5 In the strip shown in Figs. 7, 8, 9, all the ears or lugs are bent laterally and then upwardly at one side of the strip and then at the other in alternate succession. It is possible however, and preferable, to bend 10 upwardly only some of the ears or lugs and to retain the others in their laterally extending position so as to provide positioning and anchoring means for the strip.

Such a construction is shown in Figs. 10 15 to 13, in which the lower section 48 is formed like in the previous case with laterally extending ears or lugs, part of which as shown at 49, are bent upwardly against one of the lateral surfaces of the upper or 20 head section 50, part are bent laterally and upwardly as shown at 51, against the other surface of said upper section, while the remaining ones are left to project laterally 25 part at one side as shown at 52 and part at the other side as shown at 53, to provide positioning and anchoring means for the strip.

The strip illustrated is shown in position in Fig. 14 where 54 designates the lower 30 layer or bed of the floor laid on the floor foundation 55, and 56 designates the upper or finishing layer of the floor. The layer or rib portion of the strip 48 is embedded within the lower layer of the floor up to a 35 point where the lower surface of its lugs or ears 52, 53, rests against the upper surface of said lower layer.

When the strip is so laid, the portion of the strip projecting above said surface, acts 40 as a gauge determining the thickness or depth of the upper or finishing layer, and the ears or lugs 52, 53, act as supporting means for the strip insuring its vertical alignment. At the same time, said ears or 45 lugs also act as anchoring means between the strip and the material out of which the finishing layer is formed further insuring the stability of the strip and the joint between the strip and the plastic material of which 50 the floor is composed.

It is obvious that by virtue of the construction just described therefore, I obtain several important advantages over strips heretofore in use for similar purposes. In 55 fact, I produce a strip which possesses all the rigidity and more of a solid strip of corresponding thickness, and at the same time I provide the anchoring and positioning means which are a necessary feature of this 60 type of floor laying material.

Furthermore, I produce a strip which can have the head portion made of brass and the rib portion made of a less expensive material, said head portion being of the same or 65 of a different thickness, than that of the

rib or body portion. A further advantage is obtained by using a bimetallic strip of the character described, due to the fact that its upper section may be made of material selected for its wearing and ornamental 70 qualities, while its lower section may be made of material selected for its strength and relatively low cost.

In Figs. 15 to 17, I illustrate a strip, the construction of which is somewhat similar to 75 that of the strip shown in Figs. 10 to 13, except that its two sections are connected by dovetailed joints, and that the same are of the same thickness. Said strip is composed of an upper or head portion 57 and a lower 80 or rib portion 58. The upper or head portion which is in the form of a relatively narrow strip is cut at spaced intervals along its lower edge to form dovetailed notches 59, 85 extending upwardly from the lower edge.

By virtue of this construction, the lower edge of the head portion or strip will be formed in an alternate succession of dovetailed notches and dovetailed tenons or male elements of a dovetailed joint. The lower 90 or rib portion of the strip is also in the form of an elementary strip of a thickness corresponding to that of the upper portion, and the upper edge is notched to interlock with the lower edge of its upper portion. Said 95 upper edge is accordingly cut at spaced intervals to correspond with the spacing between tenons 60 of the upper strip, so as to form dovetailed notches 61 adapted to tightly fit and receive tenons 60. 100

Like in the previous case, in producing said notches, the material is cut along the upwardly converging sides 62, 63, of each notch, and the portion of material thus isolated from the body of the strip is bent 105 to one side to form laterally projecting lugs or ears such as 64, 65.

Part of said ears or lugs are bent to one side of the strip and part to the other, and the resulting tenons 66 are adapted to fit and 110 to tightly interlock with notches 59 of the upper portion, so that the two elementary strips may be laterally displaced toward each other and caused to interlock in the manner shown. Once the two portions of the strip 115 are thus assembled, part of the ears extending to one side of the strip are bent upwardly and against one of the lateral surfaces of the upper portion 57, forming retaining flanges 67, and part of the ears projecting 120 at the other side of the strip are bent upwardly in the same manner to form retaining flanges 68.

The strip illustrated in Figs. 18 to 23 is 125 similar in every respect to the one just described, except that the upper or head portion of the strip 69 has a wider section than the lower or rib portion 70. Fig. 22 clearly shows how the lower portion 70 of the strip is slit downwardly from its upper edge to 130

form notches 61', the material being bent at such points to form outwardly extending ears such as 64', 65', part of said ears 67'', 68'', being bent upwardly after assembling to form the retaining flanges 67', 68', flange 67', being clearly shown in Fig. 23.

The resulting structure is to all intents and purposes as rigid as if it were formed out of a solid body of material; furthermore, the same results formed with laterally projecting ears or lugs which provide suitable anchoring means for the strip without weakening its section.

While all the drawings show the positioning, anchoring and locking means obtained by bending or forming portions of metal isolated from the lower portion of the strip, it is obvious that analogous structures can be obtained by similarly bending or forming portions isolated from the upper portion of the strip in order to form the notches thereof, if desired.

However, as a rule it is the lower portion of the strip which is made of relatively thin gauge material, readily lending itself to bending and forming operations, while the upper portion of the strip may at times be made out of heavy gauge material.

Furthermore, the provision of such lugs or ears calls for an increase in the material required, because if the notches are simply cut off, the material obtained therefrom, can be utilized to form the tenons of another strip section, and since the upper part of the strip is usually made of more expensive material it is worth while to effect as much saving in material as possible. All these reasons therefore militate in favor of the constructions shown where the anchoring, positioning and locking means are exclusively obtained from the lower portion of the strip.

My inventive idea may be applied in ways different from those shown and therefore the drawings should be understood as being intended for illustrative purposes only and not in a limiting sense.

I accordingly reserve myself the right to carry my invention into practice in all those ways and manners which may enter, fairly, into the scope of the appended claims.

I claim:

1. A floor strip of the character described, comprising an upper and a lower longitudinal section interlocking with each other along their inner edges, and means integral with one of the said sections, preventing relative lateral displacement of the same.

2. A floor strip of the character described, comprising an upper and a lower longitudinal section interlocking with each other along their inner edges, said edges being formed with longitudinally interextending male and female joint members, and means integral with one of the said sections, pre-

venting relative lateral displacement of the same.

3. A floor strip of the character described, comprising an upper and a lower longitudinal section interlocking with each other along their inner edges, said edges being formed with dovetailed male and female joints, and means integral with one of the said sections, preventing relative lateral displacement of the same.

4. A floor strip of the character described, comprising an upper and a lower longitudinal section interlocking with each other along their inner edges, and means extending from one of said sections, overlapping the lateral surfaces of the other, preventing relative lateral displacement of said sections.

5. A floor strip of the character described, comprising an upper and a lower longitudinal section interlocking with each other along their inner edges, means extending from one of said sections, overlapping the lateral surfaces of the other, preventing relative lateral displacement of said sections, and anchoring means laterally extending from said strip.

6. A floor strip of the character described, comprising an upper and a lower longitudinal section interlocking with each other along their inner edges, means extending from one of said sections, overlapping the lateral surface of the other, and anchoring means laterally extending from said strip, part of both said overlapping and anchoring means extending at one side of the strip, and part at the other.

7. A floor strip of the character described, comprising an upper and a lower longitudinal section interlocking with each other along their inner edges, means extending from one of said sections, overlapping the lateral surfaces of the other, preventing relative lateral displacement of said sections, and anchoring means laterally extending from said strip, said anchoring means also acting as positioning means determining the depth at which the strip is to be placed in position.

8. A floor strip of the character described, comprising an upper and a lower longitudinal section interlocking with each other along their inner edges, said edges being formed with male and female joints comprising interlocking notches and tenons, one of said sections being formed with members extending from the base of said notches and overlapping the lateral surfaces of the other section, preventing relative lateral displacement of said sections.

9. A floor strip of the character described, comprising an upper and a lower longitudinal section interlocking with each other along their inner edges, said edges being formed with male and female joints comprising interlocking notches and tenons, one

of said sections being formed with members extending from the base of said notches and overlapping the lateral surfaces of the other section, preventing relative lateral displacement of said sections, and anchoring members, also integral with one of said sections, extending laterally thereof substantially at right angle thereto.

10. A floor strip of the character described, comprising an upper and a lower longitudinal section interlocking with each other along their inner edges, said edges being formed with male and female joints comprising interlocking notches and tenons, one 15 of said sections being formed with members extending from the base of said notches and overlapping the lateral surface of the other section, and anchoring members, also integral with one of said sections, extending 20 laterally thereof, substantially at right angle thereto, part of both said overlapping and anchoring members extending at one side of the strip, and part at the other.

11. A floor strip of the character described, comprising an upper and a lower longitudinal section interlocking with each other along their inner edges, said edges being formed with male and female joints comprising interlocking notches and tenons, the 25 lower section being formed with members extending from the base of said notches and overlapping the lateral surfaces of the other section, preventing relative lateral displacement 30 of said sections.

35. 12. A floor strip of the character described, comprising an upper and a lower longitudinal section interlocking with each other along their inner edges, said edges being formed with male and female joints comprising interlocking notches and tenons, the 40 lower section being formed with members extending from the base of said notches and overlapping the lateral surfaces of the other section, preventing relative lateral displacement 45 of said sections, and anchoring members, also integral with said lower section, extending laterally thereof substantially at right angle thereto.

13. A floor strip of the character described, 50 comprising an upper and a lower longitudinal section interlocking with each other

along their inner edges, said edges being formed with male and female joints comprising interlocking notches and tenons, the lower section being formed with members 55 extending from the base of said notches and overlapping the lateral surfaces of the other section, preventing relative lateral displacement of said sections, the upper section having a greater thickness than the lower sec- 60 tion.

14. A floor strip of the character described, comprising an upper and a lower longitudinal section interlocking with each other along their inner edges, said edges being 65 formed with male and female joints comprising interlocking notches and tenons, the lower section being formed with members extending from the base of said notches and overlapping the lateral surfaces of the other 70 section, preventing relative lateral displacement of said sections, and anchoring members, also integral with said lower section, extending laterally thereof substantially at 75 right angle thereto, the upper section having a greater thickness than the lower section.

15. A floor strip of the character described, comprising an upper and a lower longitudinal section interlocking with each other 80 along their inner edges, and means integral with one of the said sections, preventing relative lateral displacement of the same, said sections being made of two different metals.

16. A floor strip of the character described, comprising an upper and a lower longitudinal section interlocking with each other along their inner edges, said edges being formed with male and female joints 90 comprising interlocking notches and tenons, the lower section being formed with members laterally extending from the base of said notches, part at one side and part at the other side thereof, substantially at right 95 angle thereto, part of said laterally extending members being bent to overlap the lateral surfaces of the upper section, preventing relative lateral displacement of said two sections.

PASQUALE GALASSI.
